US0D1037811S

(12) **United States Design Patent** (10) Patent No.: **US D1,037,811 S**
(45) Date of Patent: ** Aug. 6, 2024

(54) **FLOORING CUTTER**

(71) Applicant: **INDUSTRIAL SUPPLY (QINGDAO) LTD.**, Qingdao (CN)

(72) Inventor: **Wensheng Xu**, Shandong (CN)

(**) Term: **15 Years**

(21) Appl. No.: **35/517,680**

(22) Filed: **May 26, 2023**

(80) **Hague Agreement Data**

Int. Filing Date: **May 26, 2023**

Int. Reg. No.: **DM/229848**

Int. Reg. Date: **May 26, 2023**

Int. Reg. Pub. Date: **Jun. 30, 2023**

(51) LOC (14) Cl. **08-03**

(52) U.S. Cl. **D8/51**

(58) **Field of Classification Search**

USPC **D8/51-60**

CPC **B26D 1/085**

See application file for complete search history.
